REFLECTOR

Jack F. Brady, Summit, and Michael Melack, Berkeley Heights, N.J., assignors to Elastic Stop Nut Corporation of America, Union, N.J., a corporation of New Jersey

Original design application Mar. 22, 1963, Ser. No. 74,088, now Patent No. 205,049, dated June 14, 1966. Divided and this application May 12, 1966, Ser. No. 3,608

Term of patent 14 years

(Cl. D72—1)

FIGURE 1 is a front elevational view of a nine unit reflector showing our new design; and

FIGURE 2 is a view taken along the line 2—2 of FIGURE 1.

This is a division of application Serial No. D.74,088, filed March 22, 1963, now Patent No. D.205,049 granted June 19, 1966.

The characteristic features of our design reside in the combination of the recessed relationship of each reflector member with respect to the bezel member and the spaced relationship between the perimeter of each reflector member and the adjacent, concentric periphery of the bezel member as best illustrated in FIGURE 2 and the central aperture through each reflector member and the bezel member as shown.

We claim:

The ornamental design for a reflector, as shown and described.
